UNITED STATES PATENT OFFICE.

TOBIAS J. BRICCA AND JOSEPH C. FAVILLA, OF SAN FRANCISCO, CALIFORNIA.

COMBINATION AUTOMOBILE TRUNK AND TABLE.

Application filed July 27, 1926. Serial No. 125,377.

This invention relates to an automobile trunk which may be conveniently converted into a table and a plurality of benches adapted for seating purposes.

5 An object of this invention is to provide an automobile trunk of the type attachable to an automobile, in which is embodied a novel construction adapted to be conveniently converted into a table and benches for 10 seating purposes.

Another object of this invention is to provide a trunk of novel construction and design which can be readily converted into a table and a plurality of seats.

15 Another object of this invention is to provide a container which may be conveniently converted into a table and benches by detaching the top and bottom from the sides thereof.

20 With the above-recited objects and others of a similar nature in view, the invention consists of the construction, combination and arrangement of parts set forth in and falling within the scope of the appended claims.

25 In the accompanying drawings:

Fig. 1 is a perspective view of a trunk embodying our invention, in which a part thereof is broken away to show the construction thereof;

30 Fig. 2 is a bottom view of the top of the trunk showing one way the supporting legs of a bench and a table may be carried;

Fig. 3 is a perspective view of a table assembled from the parts of the trunk, the 35 sides of the trunk being shown in dotted lines and a part of the table being broken away to show the construction thereof; and

40 Fig. 4 is a perspective view of the supporting structure of one of the benches, the top thereof being shown in dotted lines.

Referring to the drawings the numerals 1, 2 and 3 designate respectively the top, bottom and sides of a rectangular shaped container or trunk. The sides 3 of the trunk 45 are divided vertically into two sections joined together by two hinge members each of which is comprised of two bars 4 suitably secured to the inside surface of the said sides 3 and movably attached together at their 50 ends by rivets 5. The hinge members are secured to the sides 3 near the top edge thereof and adjacent the point where they are vertically divided into two sections, thereby permitting the two sections comprising the 55 sides 3 to be swung upwardly until the top edges of the said sections contact with each

other and form the top of a table, as shown in Fig. 3. Extending horizontally inside the ends of the sides 3, near the bottom edge thereof, are four openings or recesses 6 into 60 which the ends of the legs 7 fit. These recesses, four in number, extend vertically when the sides 3 are unfolded, and serve to maintain the legs 7 in a vertical position.

As shown in Fig. 2, the legs 7 may be 65 maintained against the underneath surface of the top 1 by placing them under two cross-bars 8 which are secured to and spaced apart from the said top by suitable screws or bolts.

To provide suitable supports for the top 70 1 and bottom 2 when they are to be used as seats or benches, we attach the ends of four vertically extending legs 9 and two horizontally extending bars 10 together by two rods 75 11, each of which extends loosely through two of the legs 9 and through two of the horizontally extending bars 10. The legs 9 are held in an upright position by hinge members 12, which are comprised of two hinge bars joined loosely at their ends by a pin. 80 The opposite ends of the said hinge bars are loosely attached to the bars 10 and the legs 9, and the hinge members 12 permit the legs to be folded adjacent the said bars when the supports are to be placed in the top or bottom 85 of the trunk. The dimensions of the support comprised of the bars 10, the legs 9 and the rods 11, are such as to permit the top 1 or bottom 2 to fit over the top of the said support, thereby providing a suitable 90 bench or seat.

As shown in Fig. 2, a seat or bench may be constructed in accordance with our invention by loosely fastening the legs 9 by any suitable means such as bolts to the downwardly extending edges of the top 1 or the bottom 2, and affixing the hinge members 12 to both the legs and the said downwardly extending edges of the top or bottom. This latter described form permits the legs 9 to be folded inside the downwardly extending edges of the top or bottom and adjacent its inside surface, thereby providing a compact and convenient construction.

As shown in Fig. 1 the inside of the container or trunk, after the supports for the table and benches are folded and placed against the top and bottom, is of sufficient size to accommodate a container 13, which may be used to hold dishes, clothing or anything else desired.

The top 1 and the bottom 2 may be held

in traveling position over the sides 3 by any suitable means such as bands or clamping devices.

While the construction herein shown and described represents the preferred form of convertible trunk, it is obvious that many changes in the form, size and proportions may be made within the scope of the appended claims without departing from the spirit or sacrificing any of the advantages of our invention.

Having described our invention, what we claim and desire to secure by Letters Patent is:

15. 1. A combination trunk and table comprising, a container having a detachable top and a detachable bottom, a plurality of side members joined together by hinges which are adapted to be converted into a table top, and supports carried inside the container for supporting the top, bottom and the table top.

25. 2. A convertible trunk comprising, a detachable top, a detachable bottom, a plurality of joined side members adapted to be converted into a table top, means for supporting the side members after they have been converted into a table top, separate means for supporting the detachable top and

separate means for supporting the detachable bottom.

30. 3. A convertible trunk comprising, a plurality of side members joined together by hinges, which said side members are adapted to be converted into a table top, a detachable top, a detachable bottom, and a plurality of supporting members carried by the top and the bottom for supporting the top, the bottom, and the side members after they have been converted into a table top.

35. 4. A convertible trunk comprising, a detachable top, a detachable bottom, a plurality of side members joined together by hinges and adapted to be converted into a table top, and supports carried by the top and the bottom for supporting the top, the bottom and the table top.

40. 5. A convertible trunk comprising, a detachable top, a detachable bottom, a plurality of side members connected together by hinges and adapted to be converted into a table top, and means for supporting the side members after they have been converted into a table top.

TOBIAS J. BRICCA.
